UNITED STATES PATENT OFFICE.

ANDREW FYRBERG, OF WORCESTER, MASSACHUSETTS, ASSIGNOR TO WARNER ARMS CORPORATION, OF NEW YORK, N. Y.

AUTOMATIC HAND-FIREARM.

1,131,360.

Specification of Letters Patent.

Patented Mar. 9, 1915.

Application filed September 25, 1914. Serial No. 863,456.

To all whom it may concern:

Be it known that I, ANDREW FYRBERG, a citizen of the United States, and a resident of Worcester, in the county of Worcester, 5 and State of Massachusetts, have invented a new and Improved Automatic Hand-Firearm, of which the following is a full, clear, and exact description.

The invention relates to automatic hand firearms such as shown and described in the Letters Patent of the United States, No. 1,105,416, granted to me on July 28, 1914.

The object of the present invention is to provide certain new and useful improvements in automatic hand firearms of the type mentioned, whereby the breech block can be readily disconnected from the recoil spring device to allow of moving the breech block rearwardly by hand with a view to permit the first cartridge in the magazine to pass to position for being pushed into the barrel on returning the breech block and whereby the complete withdrawal of the breech block and the firing pin carried thereby can be had for repairs or other purposes, and whereby the barrel can be quickly and securely fastened in position on the frame.

In order to accomplish the desired result use is made of a breech block provided at its rear end with a permanent head, a recoil device connected with the said head and manually controlled means for connecting and disconnecting the said breech block head relative to the said recoil device. Use is also made of a breech block provided with a spring-pressed firing pin and with a slot, an abutment lever adapted to project with one end into the said slot and into the path of the rear end of the firing pin spring, and a manually controlled means for locking and unlocking the said abutment lever to permit of withdrawing the breech block.

The invention further consists of other novel features and parts and combinations of the same as will be more fully described hereinafter and then pointed out in the claims.

A practical embodiment of the invention is represented in the accompanying drawings forming a part of this specification, in which similar characters of reference indicate corresponding parts in all the views.

Figure 1 is a side elevation of the automatic hand firearm with parts shown in section; Fig. 2 is an enlarged cross section of

the same on the line 2—2 of Fig. 1; Fig. 3 is a like view of the same on the line 3—3 of Fig. 1; Fig. 4 is a side elevation of the rear end of the automatic hand firearm with the breech block partly withdrawn and disconnected from the recoil device; and Fig. 5 is an enlarged perspective view of the locking pin for the abutment lever for the firing pin spring.

The frame A of the firearm is provided with an integral handle B containing the usual removable magazine for carrying a stack of cartridges. The frame A is further provided with a forward projection C having in its top a recess C' into which fits the base D' of the barrel D provided with the usual bore for receiving the cartridges in the usual manner. The rear wall of the recess C' is provided at the top with a cross bar C² into which fits a groove or slot D² 75 formed in the rear face of the barrel D so as to hold the barrel against upward movement, it being understood that the rear face of the said barrel fits snugly against the forward face of the casing A, as plainly indicated in Fig. 1. A screw E extends transversely through the projection C and the base D' and screws at its end in one side of the projection C to quickly lock the base D' in position in the projection C on top of 80 which rests the barrel D.

The end of the bore of the barrel D is in axial alignment with the breech block F mounted to slide longitudinally in the frame A in the rear of the barrel D, and in the 90 said breech block F is mounted to slide a firing pin G pressed on by a spring H and controlled by a sear I adapted to be manipulated from the trigger J in a manner more fully set forth in the patent above referred to, so that further description of this part of the firearm is not deemed necessary. The rear end of the breech block F is provided with a permanent head F' normally connected with a recoil device, preferably in the 100 form of two recoil rods K, mounted to slide longitudinally in the upper portion of the frame A directly above the breech block F and hence in the rear of the barrel D. The forward ends of the recoil rods K are provided with heads K' against which abut the forward ends of springs L resting at their rear ends on shoulders A' formed in the top of the frame A. The rear ends of the recoil rods K are provided with transversely ex- 110

tending notches K^2 (see Figs. 3 and 4) adapted to be engaged by a pin N extending transversely and mounted to turn in the head F' of the breech block F . The pin N is provided in its peripheral face with notches N' adapted to register with the rear ends of the recoil rods K which latter normally project beyond the rear end of the frame A to allow the corresponding recesses in the head F' to be then engaged by the pin N with a view to fasten the head F' to the rear ends of the recoil rods K . One outer end of the locking pin N is provided with a handle N^2 under the control of the operator for turning the pin from locking into unlocking position or vice versa. When the handle N^2 is swung rearwardly then the pin N engages notches K^2 in the rear ends of the recoil rods K to fasten the said recoil rods in position in the head F' , but when the handle N^2 is swung into a forward position as shown in Fig. 4 then the notches N' register with the rods K and consequently the latter are unlocked and the breech block F can be moved rearwardly without actuating the recoil device, that is without drawing the recoil rods K rearwardly and pressing the springs L thereof. It is understood that this rearward movement of the breech block F is desirable when replacing a refilled magazine in position in the handle B , to allow the uppermost cartridge to pass in front of the breech block F to be pushed by the latter into the bore of the barrel D on returning the breech block F to normal forward position. When this has been done the operator swings the handle N^2 from forward to rearward position to again fasten the head F and the recoil rods K together. It is understood that when the cartridge is fired the breech block F moves rearwardly and presses the springs L of the recoil device to allow another cartridge to pass from the magazine in front of the breech block for the latter to push the second cartridge into the barrel during the return of the breech block F by the action of the springs L . The pin N is held against withdrawal from the head F' by a longitudinal pin N^3 driven into the head F' and extending through an annular groove N^4 formed in the pin N (see Fig. 3), thus allowing turning of the pin N but holding the same against transverse movement in the head F' . A forward movement of the recoil rods K is prevented in case the barrel D is removed by the use of a transverse pin O held in the frame A and engaging notches K^3 formed in the heads K' , as plainly shown in Figs. 1 and 2. The arrangement described besides holding the recoil rods K against forward movement also holds the recoil rods K against turning at the time the breech block head F' is disconnected from the rear ends of the recoil

rods K to insure proper registering of the pin N with the notches K^2 on returning the breech block F and fastening the head F' and the rear ends of the recoil rods K together as previously explained. 70

The rear end of the firing pin spring H abuts against the upper end of a lever P fulcrumed at P' on the rear end of the casting A to permit of swinging the lever P in and out of engagement with the rear end of the firing pin spring H . The lever P is provided with a short knob or fingerpiece P^2 extending to the outside of the frame A to permit the operator to impart a swinging motion to the lever P . The lower end of the lever P is pressed on by a spring Q abutting against the sear I , and the lower terminal of the lever P normally rests against the peripheral face of a transverse pin R mounted to slide transversely in the frame A . The pin R is pressed on by a spring S (see Fig. 5) to hold the peripheral face of the pin normally in position against the lower end of the lever P , and the outward movement of the pin R is limited by the head of a screw T screwing in the frame A and engaging a recess R' formed in the outer end of the pin R (see Figs. 4 and 5). The pin R is provided with a cut-out portion R^2 adapted to move into register with the lower end of the lever P on pressing the pin R inward against the tension of its spring S so that the operator can impart a swinging motion to the lever P with a view to disengage the upper end thereof from the rear end of the firing pin spring H whenever it is desired to withdraw the breech block F from the frame A for repairs or other purposes. It is understood that the upper end of the lever P extends through a slot F^2 in the breech block F (see Fig. 3) to move into the path of the rear end of the firing pin spring H , as previously explained. It is also understood that when the pins N and R are in unlocking position and the lever P is swung downward then the breech block F can be pulled completely out of the frame A for repairs or other purposes. When the pin R , however, is in locked position the lever P is held against swinging and consequently the breech block F can only be drawn out partly when the locking pin N is in unlocking position, as previously explained and the breech block cannot drop accidentally out of the frame when in unlocked position. It is further understood that the breech block F is provided with the usual extractor U (see Fig. 2) for drawing out the empty shell after the shot is fired and the recoil action takes place. 115

Having thus described my invention, I claim as new and desire to secure by Letters Patent:

1. A firearm provided with a frame having a breech block bearing and a recoil rod bear- 130

ing above the said breech block bearing, a barrel held on the said frame in front of the said breech block bearing, a breech block 5 slidable in the said breech block bearing and having at its rear end a fixed head abutting against the rear end of the said recoil rod bearing, a spring-pressed recoil rod slidable in the said recoil rod bearing and having its rear end projecting into the said breech block head, and locking means 10 mounted transversely on the said breech block head and adapted to be turned normally in opposite directions, the said locking means in one position engaging the said recoil rod to lock the breech block head and the recoil rod together, and the said locking means in another position disengaging the said recoil rod to unlock the breech block head relative to the recoil rod to allow movement 15 of the breech block independently of the recoil rod.

2. A firearm provided with a frame having a breech block bearing and a recoil rod bearing above the said breech block bearing, 25 a barrel held on the said frame in front of the said breech block bearing, a breech block slidable in the said breech block bearing and having at its rear end a fixed head abutting against the rear end of the said recoil rod bearing, a spring-pressed recoil rod slidable 30 in the said recoil rod bearing and having its rear end projecting into a recess in the said breech block head, the said rear end of the recoil rod being provided with a notch, a 35 transverse locking pin mounted to turn in the said breech block head and intersecting the said recess, the said pin having a cut-out portion adapted to register with the said recoil rod to allow the notched end thereof to 40 pass into the recess, the said pin on being turned engaging the said notch to fasten the head and recoil rod together, and a handle on one outer end of the said pin to permit of turning the pin into locking or unlocking 45 position.

3. A firearm provided with a casing having a breech block bore, a breech block slidable in the said bore and provided with a firing pin bearing and a slot leading thereto, 50 a recoil device slidable in the said frame, a manually controlled locking device on the said breech block and engaging the said recoil device to normally lock the breech block and recoil device together, a firing pin 55 slidable in the said firing pin bearing, a spring pressing the said firing pin, and a manually controlled abutment lever fulcrumed on the casing and normally projecting through the said slot into the bearing to 60 form an abutment for the rear end of the said firing pin spring and to prevent the said breech block from falling out of the said bore at the time the breech block is disconnected 65 from the recoil device by the said locking device, the said abutment lever hav-

ing a fingerpiece extending to the outside of the said casing.

4. A firearm provided with a casing having a breech block bore, a breech block slidable in the said bore and provided with a 70 firing pin bearing and a slot leading thereto, a recoil device slidable in the said frame, a manually controlled locking device on the said breech block and engaging the said recoil device to normally lock the breech block 75 and recoil device together, a firing pin slidable in the said firing pin bearing, a spring pressing the said firing pin, a manually controlled abutment lever fulcrumed on the casing and normally projecting through the 80 said slot into the bearing to form an abutment for the rear end of the said firing pin spring and to prevent the said breech block from falling out of the said bore at the time the breech block is disconnected 85 from the recoil device by the said locking device, the said abutment lever having a fingerpiece extending to the outside of the said casing, and a locking device engaging 90 the said abutment lever when in one position to normally hold the abutment lever against movement, the last mentioned locking device when in another position allowing the said abutment to swing out of position relative to the firing pin spring and 95 the breech block.

5. A firearm provided with a casing having a breech block bore, a breech block slidable in the said bore and provided with a firing pin bearing and a slot leading thereto, a firing pin slidable in the said firing pin bearing, a spring in the said bearing and pressing the firing pin, a manually controlled abutment lever fulcrumed on the casing and normally projecting through the 100 said slot into the bearing to form an abutment for the said spring and to prevent the breech block from being drawn out of the said bore the said abutment lever having a fingerpiece extending to the outside of the 110 said casing, and a spring-pressed pin mounted to slide transversely in the said casing and normally engaging the said lever to hold the latter against swinging, the said pin having a cut-out portion adapted to 115 move into register with the said lever on pressing the pin to allow the lever to swing into inactive position relative to the said firing pin spring and breech block.

6. A firearm provided with a frame having a forward projection a distance from the top of the frame, the said projection being provided with a recess terminating at its forward end a distance from the forward end of the said projection, the rear wall of the said recess being provided with an integral cross bar, a barrel adapted to rest on the said projection and abutting with its rear end against the forward end 125 of the frame above the said projection, the 130

5 said barrel being provided with a base fitting into said recess, the rear end of said base being provided with a notch fitting the said cross bar the forward wall of the said recess and the forward end of the said base being beveled upwardly and forwardly, and a transverse screw engaging the said barrel base and the said frame projection.

7. A firearm provided with a frame having a recoil rod bearing, a spring-pressed recoil rod slidable in the said bearing and provided at its forward end with a head having a notch opening onto the front face of the said head, the rear end of the said rod projecting beyond the said bearing and having a notch, a breech block slidable in the said frame and having a head provided with

20 a turnable pin adapted to engage the notch in the rear end of the recoil rod, and a pin held in the said frame and engaging the 25 notch in the head of the recoil rod to hold the latter against turning at the time the breech block head is disengaged from the rear ends of the recoil rod the said notched head moving out of engagement with the said pin on a rearward movement of the said breech block.

In testimony whereof I have signed my name to this specification in the presence of two subscribing witnesses.

ANDREW FYRBERG.
